UNITED STATES PATENT OFFICE.

PETER MARZETZ, OF CHICAGO, ILLINOIS.

STATION-INDICATOR FOR CARS.

1,160,739.

Specification of Letters Patent. Patented Nov. 16, 1915.

Application filed November 25, 1914. Serial No. 873,972.

To all whom it may concern:

Be it known that I, PETER MARZETZ, subject of the Emperor of Austria-Hungary, residing at Chicago, in the county of Cook 5 and State of Illinois, have invented certain new and useful Improvements in Station-Indicators for Cars, of which the following is a specification.

This invention relates to certain new and 10 useful improvements in station indicators for cars.

The primary object is to provide a device positioned within a vehicle or car such as a street railway car whereby the person in 15 charge may properly indicate to the passengers the name of the next station to be reached in the regular course of travel.

A further object is to provide an indicating device with the names of all of the stations upon any line of travel such names being adapted for shifting to a viewable position by means of an operating lever and the complete list of names being capable of reversal within the indicator at each termination 25 of the route.

A still further object is to provide winding means for an indicator curtain operable in a step-by-step movement transversely of a visual opening and having a resilient 30 presser means engaging the curtain adjacent to such opening and having a light positioned adjacent thereto.

With these general objects in view and others that will appear as the nature of the 35 invention is better understood, the same consists in the novel combination and arrangement of parts hereinafter more fully described, illustrated in the accompanying drawings and set forth in the appended 40 claims.

In the drawings forming a part of this application and in which like designating characters refer to corresponding parts throughout the several views, Figure 1 is a 45 central longitudinal vertical sectional view of the device detached with a portion of the hinged side of the casing shown in elevation. Fig. 2 is a side elevation of the device attached to a portion of the car wall, the latter 50 being shown in vertical section. Fig. 3 is an enlarged sectional detail view of the winding drum and its actuating means. Fig. 4 is an enlarged side elevation of the 55 actuating means shown in its operating position and illustrated in dotted lines in its normal position, and Fig. 5 is a perspective

view of the detachable end of the curtain and showing the roller upon which the same is mounted.

Referring more in detail to the drawings 60 there is illustrated a device mounted upon the end 11 of a car and including a casing 12 which is provided with projecting perforated ears 13 for receiving screws for retaining the casing upon the said end. 65

A curtain 15 provided with the names of all of the stations along the line of travel of the car is positioned within the casing being mounted upon an upper roller 16 which is manually driven in a single direction in a 70 step-by-step movement and in a manner hereinafter described, the curtain being thus wound upon the said upper roller and unwound from a lower roller 17. The said upper roller is provided with a plurality of 75 spring clips 18 adapted to receive the perforations or eyelets 19 provided through the end of the curtain 15 and whereby the end of the curtain may be readily attached to and detached from the said roller 16. The 80 roller 16 is secured to an axle 20 which is journaled in the upper cylindrical portion 21 of the casing, while the roller 17 is slidably and rotatably mounted upon a stationary axle 22 positioned upon the longitudinal 85 axis of the lower cylindrical portion 23 of the casing, the said axle 22 being fixedly mounted within the casing and centrally of the end disk 24 of the said casing portion 23. By this arrangement it will be 90 evident that as the end of the curtain which is opposite to the perforated end thereof is secured to the roller 17, the side 25 of the casing which is hingedly mounted as at 26 may be opened and after the curtain is completely wound upon the roller 16 as at the 95 end of the route, the operating means may be disengaged from the roller 16 and the curtain rewound upon the roller 17 and then the perforated end of the curtain is removed 100 from the roller 16 and the roller 17 is slidably removed from the axle 22 and the curtain and turned around so as to expose the opposite side thereof to the window or opening 27 of the casing, whereupon the roller 17 105 is again returned to the axle 22 and the perforated end of the curtain is again secured to the roller 16 and the device is ready for the return trip of the car.

The window 27 of the casing is positioned 110 in the contracted middle portion 28 thereof between the casing portions 21 and 23 and

one or more lamps 29 are positioned upon the outer side of the casing and within a protecting reflector 30 at a point directly above the window 27.

5 For insuring an accurate tracking of the curtain in flat relation respecting the opening 27, a shoe plate 31 is mounted within the casing flatly engaging the curtain within the casing portion 28 and is spring pressed 10 against the curtain by means of coil springs 32.

The axle 20 of the upper roller 16 has one end 33 thereof extending exteriorly of the casing portion 21 and is provided thereon 15 with a toothed wheel 34 fixed thereto while a collar 35 is journaled upon the said axle end between the wheel 34 and a ring 35' secured to the said end by means of a screw 36.

An operating dog 37 has an arm 38 thereof 20 pivoted to a finger 39 of the said collar and adapted to engage the teeth of the wheel 34 and to revolve the said wheel to the extent of two teeth at each pull upon the dog exerted by means of the cord 40. This cord 25 has one end thereof secured to the end 41 of the dog and then passes over pulleys 42 secured to the car wall above the level of the indicator casing and said cord may preferably be passed within the said wall and 30 has its lower end secured to an operating lever 43. The said lever has one end thereof pivoted as at 44 to the casing and its other end provided with a handle 45 and projecting through a slot 46 of the wall which 35 limits the pivotal movement of the lever to a distance sufficient to actuate the dog the required amount. The dog end 41 has a return coil-spring 47 attached between the same and the adjacent side of the casing 40 portion 21 and whereby after each pull of the cord the dog is returned to its normal position in a ratcheting backward movement over the teeth of the wheel 34, until the stop 45 60 upon the casing is engaged by the rear end 61 of the dog.

It is to be understood that the names of the stations such as the name "York" indicated at 48 are printed upon the opposite sides of the curtain 15 as illustrated in Fig. 50 6 while the names of the succeeding stations upon the roof are successively so placed upon the curtain. The name of the next station to be reached by the car in its travel 55 may be seen by viewing the window 27 and when such place is reached, the conductor or person in charge of the car gives a downward movement to the lever handle 45 which turns the wheel 34 and the roller 16 suffi-

ciently to wind up enough of the curtain 15 upon the roller 16 and off of the roller 17 60 to position the next name upon the curtain directly behind the window 27. This operation is repeated as each station is reached so that the name of the next succeeding station is always viewable by the passengers, it 65 being noted that the entire curtain is reversed for presenting the opposite side thereof to the window at the termination of the trip and in the manner hereinbefore described. 70

While the form of the invention herein shown and described is what is believed to be the preferred embodiment thereof, it is nevertheless to be understood that minor changes may be made therein without departing from the spirit and scope of the invention as set forth in the claims. 75

What I claim as new is:—

1. A device of the class described comprising a casing having cylindrical upper 80 and lower end portions and a communicating contracted portion, an end closure hinged to the said casing, a window at the forward side of said contracted portion, a power axle in said upper casing portion, a 85 roller secured upon said axle, spring clips upon said roller, an axle fixedly positioned within said lower casing portion, a slidably removable roller journaled upon said lower axle, an indicator curtain wound upon said 90 lower roller and having one end thereof secured to said spring clips of said upper roller, a presser plate within said contracted portion in engagement with the rear side of said curtain, and resilient tensioning means 95 for the said plate.

2. A device of the class described comprising enlarged end portions and a contracted connecting neck portion, there being a viewable opening in the neck portion, a reflector carried by one of the end portions and arranged adjacent said opening, a web roller journaled in each of said end portions, a web connected at its ends to said rollers and wound thereon, said web passing 100 through the contracted neck portion and a spring-pressed shoe in engagement with the rear face of the web to cause the same to engage the neck portion throughout the length thereof. 105

In testimony whereof I affix my signature in presence of two witnesses.

PETER MARZETZ.
